UNITED STATES PATENT OFFICE.

JOHN WATERHOUSE, OF CHICAGO, ILLINOIS.

IMPROVEMENT IN WATER-METERS.

Specification forming part of Letters Patent No. 146,624, dated January 20, 1874; application filed May 24, 1873.

To all whom it may concern:

Be it known that I, JOHN WATERHOUSE, of Chicago, in the county of Cook and State of Illinois, have invented a new and useful Improvement in Water-Meters, of which the following is a specification:

This invention relates to apparatus designed for measuring water from service-pipes as it is delivered to the consumer; and consists in the construction and arrangement of parts hereinafter described.

In the accompanying drawing, Figure 1 is a vertical section of the meter, taken on the line *y y* of Fig. 2. Fig. 2 is a vertical cross-section of Fig. 1 taken on the line *x x*.

Similar letters of reference indicate corresponding parts.

A represents the meter, consisting of a rectangular-shaped metallic box divided into two compartments, *B* and *C*, by the central vertical partition *D*. *E* is the induction, and *F* the eduction, pipes. These pipes connect with the horizontal pipe *G*, which is fixed in the partition *D*. From the horizontal tube *G* two pipes, *H* and *I*, extend downward to near the bottom of the meter in each compartment, as seen in Fig. 1. *J* is a weight in each compartment, the two being connected together by the rod *K*, which rise and fall alternately, and operate a rotating slotted tube, *L*, in the pipe *G*, and control the flow of the water. *M* is a float hinged to the side of the meter in each compartment. *N* is a lever for each float, the fulcrums of which are at the points *O O*. These levers are connected with the floats by means of the bars *P P*. (See Fig. 1.) *Q* is an air-tube connected with each compartment, by means of which air may pass from one to the other.

We will suppose a quantity of water to be in each compartment. The water from the induction-pipe runs into and fills one compartment, forcing the air contained therein through the air-pipe *Q* into the other compartment, and this compressed air forces the water up through the eduction as it is being used. When the water in one compartment descends to a certain depth, the float will follow and pull the long arm of the lever outward, which releases the short arm, and allows the weight to fall. At the same time the weight in the other com-

partment, which is submerged in water, ascends and catches on the short end of the lever, which operation changes the flow of the water.

The tube *G* is open at both ends, but closed at the middle. The tube *L*, which is the axis upon which the weights move, fits snugly into the pipe *G*, and both are provided with suitable slots or openings, for changing the flow of the water. The floats *M* are but little lighter than the water, and are prevented from rising much above a horizontal position by the lever-bars *P*, which strike against the sides of the meter. A small rod, *R*, is fastened in the center of the pivot-tube *L*, from whence it passes through the front of the meter in a water-tight packing, and terminates in a suitable device for connecting with any approved registering apparatus.

These meters may be made of any kind of metal. The water in the bottom should be of sufficient depth to receive the ends of the pipe, to prevent the escape of the air.

For adjusting the floats, so that they will trip the weights at the proper time, fill the meter full while it is open or before the top is put on, and then draw off, say, five gallons from each compartment, and adjust the floats to trip at this stage of the water. When the required quantity of water is in the meter, and a sufficient head of water is allowed to flow into one of the compartments while the egress is cut off, all the air in one compartment will be forced into the other, and this will give a pressure sufficient to raise the water about thirty-four feet. If it is required to raise the water higher than this, then a sufficient quantity of air is forced in to give the desired pressure. This is done by connecting an air-pump with the tube *S* when, say, the left compartment is nearly empty; then turn the cock *T* of the tube, and disconnect the pump. Now, let the water be drawn off until the other compartment is emptied, and the moment the weight falls cut off communication between the two compartments by the cock *U*. The water will not fill the left compartment if a superfluous quantity of air has been forced in, so the cock *U* is opened, and such air is drawn off.

By means of a meter constructed in this manner, the water is accurately measured as it flows,

and may be elevated to any desired height, in the manner described.

To the ends of the air-tube Q are attached wire baskets, in each of which is a ball-valve, that closes the end of pipe whenever the water rises up thereto.

Having thus described my invention, I claim as new and desire to secure by Letters Patent—

1. A water-meter of two compartments with weights J J and floats M M therein, and a stationary slotted tube, and a slotted pivot-tube, so arranged that the oscillation of the weights controls the flow of the water, substantially as shown and described.

2. The air-tube Q, opening into each compartment B C, and provided with a wire basket at each end, having thereon a ball-valve that prevents the escape of water from one chamber to the other.

3. The floats M M, and catch-levers N N, in combination with the weights J J, as and for the purposes described.

JOHN WATERHOUSE.
